FOUNDATION ROLLER, SHAPER, AND EARTH STABILIZER

Robert H. H. Hugman, San Antonio, Tex.

Application October 3, 1950, Serial No. 188,213

2 Claims. (Cl. 94—50)

1

This invention relates to a foundation roller, shaper and earth stabilizer, and has for one of its objects the production of a simple and efficient means for rolling and shaping earth preparatory to pouring concrete thereon, in a manner whereby the concrete slab which is formed is provided with vertical reinforcing beams on centers both ways to add greatly to the strength of the slab.

A further object of this invention is the production of a simple and efficient machine which is constructed in a manner to facilitate the forming, shaping and stabilization of a foundation area, upon which area a concrete slab is adapted to be formed.

Other objects and advantages of the present invention will appear throughout the following specification and claims.

In the drawings:

Figure 1 is a side elevational view of one type of machine with which the roller is used;

Figure 2 is a longitudinal sectional view through the roller, a portion thereof being shown in elevation, and the roller being mounted in association with a modified type of frame and machine;

Figure 3 is a fragmentary vertical sectional view partly in elevation taken on line 3—3 of Figure 2;

Figure 4 is a fragmentary top plan view of a shaped area formed by the improved roller;

Figure 5 is a fragmentary longitudinal sectional view partly in elevation illustrating a modified type of roller which is provided with a heating means;

Figure 6 is a fragmentary end elevational view of the structure shown in Figure 5;

Figure 7 is a perspective view of the roller shown in Figure 2, with a draft element and in its simplified form.

By referring to the drawings in detail, it will be seen that 10 designates the frame of one type of machine with which the improved shaper roller 11 is adapted to be used. The frame 10 is supported upon suitably retractable front and rear wheels 12 and 12^a of a conventional type which may be raised and lowered by means of suitable hydraulic actuating means 13 also of a conventional type. The hydraulic actuating means is adapted to be controlled by the operator through the medium of a conventional control 14 adjacent the operator's seat 15. A motor 16 is mounted upon the frame 10, and a suitable transmission mechanism 17 is provided for driving the universally connected drive shaft 18 for the rear wheels 12^a of the machine. The shaft 19 also is driven

2

through the medium of the transmission mechanism 17 for driving the sprocket and chain drive 20 to operate the sheep foot traction roller 21 of the conventional type. The traction roller 21 is mounted forwardly of the shaper roller 11 and rearwardly of the front wheels 12. As is common with machines of this general type, two rear wheels such as the wheel 12^a which is shown in Figure 1, are provided, and two front wheels such as the front wheel 12, also are provided. Since these are of the conventional type, it is thought unnecessary to illustrate both of the front and both of the rear supporting wheels. A suitable sighting arrangement in the nature of standards A and B are supported in spaced relation in line of sight of the operator to facilitate straight driving of the machine.

It should be understood that a frame such as 10 may be supported by the shaper roller 11^a. A motor 22 is mounted upon the frame 10^a and a tank 23 or tanks 23 and 24 are carried by the frame 10^a for feeding asphalt emulsion or other selected emulsion to the roller 11^a. The roller 11^a is an important feature of the invention, whether operated with a specially constructed machine or considered and operated singularly to accomplish the desired purpose.

The roller 11^a comprises a hollow drum-like body formed of metal or the like, having a plurality of outwardly pressed longitudinally extending spaced ribs 26 formed therein, and a plurality of outwardly pressed circumferentially spaced ribs 27 also formed therein. The ribs 26 and 27 are hollow, as shown. The ribs 26 are provided with inwardly converging side walls 28, and the ribs 27 are provided with outwardly converging side walls 29. The ribs 26 are therefore wider at their outer ends and recede toward the body of the roller 11, whereas the ribs 27 taper toward their outer ends. This construction will facilitate the rolling of the roller 11^a over the earth to form clearly defined impressed channels or indentations in the surface of the earth in a waffle-like pattern, as shown in Figure 4. The formation of the ribs 26 will facilitate the withdrawal of the ribs 26 from the surface of the earth as the roller 11^a rotates in the direction of the arrow shown in Figure 3. The ribs 26 will cause channels 30 to be pressed into the surface of the earth, the side walls of which flare upwardly and outwardly as the roller 11^a rolls in the direction of the arrow, in the manner also shown in Figure 3. The circumferential ribs 27 will form longitudinal channels 31 of a similar shape due to the shape of the ribs 27 which taper

outwardly. The roller 11^a is carried by a longitudinal axle 32 which is journaled at its opposite ends in the hanger arms 33 of the frame 10.

A plurality of spoked wheels 34 are carried by the axle 32 within the roller 11^a, as shown in Figure 2. The spokes of one wheel 34 preferably are arranged in staggered relation to the spokes of the adjoining wheels, or are alternately out of alignment relative to the length of the roller 11^a. The outer ends of the spokes 34^a fit in the outwardly pressed portions of the roller at the junction of the longitudinal and circumferential ribs to brace the roller at these points. Other ribs 34^b extend into the circumferential hollow ribs 27 to brace the ribs 27 intermediate the ribs 26, as shown in Figure 3. Longitudinal bracing members 35 are welded to the spokes 34^a and 34^b and to the inner face of the drum-like body of the roller 11^a. A reinforcing circumferential band 36 is fitted within each circumferential hollow rib 27, as shown in Figure 2, and these bands 36 are fixed to the spokes as shown. The roller 11^a, therefore, will be thoroughly braced while being relatively light in weight to facilitate transportation when not in use. A closure plate 37 preferably closes each end of the roller 11^a to tightly seal the interior, and removable plugs 38 are carried by each plate 37 to facilitate the filling of the roller 11^a with water to obtain the desired weight. These plugs 38 may be removed for draining the roller when it is desired to transport the roller without the added weight of the contained water.

In operation, and by referring to Figure 1, it will be seen that means in the nature of supporting wheels 12 and 12^a are provided for transporting the machine from place to place, and for properly locating the shaper roller 11 with respect to previously formed earth impressions. The wheels 12 and 12^a will facilitate the location of the roller 11 in a properly registered position with respect to previously formed earth impressions so as to keep a proper alignment of the waffle-like pattern of impressions which are being formed in the surface of the earth which is being treated prior to laying the concrete area. The roller 11 is of the same structure previously described relative to roller 11^a, or other types of roller may be substituted such as that shown in the modified form—note Figures 5 and 6. It is necessary that the roller be built so that each set of impressions made by the roller will line up in both directions with the set of earth impressions previously made, especially when the roller is of a size which will not form a pattern of a desired width or area. The longitudinal ribs of the roller must be placed so as to line up with the previously formed transverse impressions formed in the earth and the outer circumferential rib must fit into the last continuous impression. This may be accomplished by lifting the shaper roller and moving the machine to the desired position and then lowering the roller 11 to the desired position. This operation is facilitated by raising and lowering the supporting wheels 12 and 12^a to raise and lower the frame 10. The roller 11 is suspended from the hanger frame 40. The sheep foot traction roller 21 will facilitate traction as well as preparing the earth surface in advance of the shaper roller 11. If desired the roller 11 may be made retractable without departing from the spirit of the invention. The shaper foundation roller is preferably located under the center of balance of the total machine. The sheep foot

traction roller 21 is suitably suspended from the frame 10 by means of a hanger 43.

A suitable horizontal tank 41 is carried by the frame 10, and a similar tank may be provided upon the opposite side of the motor. Asphalt emulsion is contained in the tank 41 and is fed to a spray pipe 42 located longitudinally above the central axis of the shaper roller 11. This emulsion, as it spreads over the surface of the roller 11, will contact and be forced into the surface of the earth as the roller rolls over this surface, thereby impregnating the surface below the roller for a certain depth, as at 44, thereby stabilizing the surface and retaining the waffle-like pattern without interruption, breakage or distortion. A slab of concrete may then be poured directly upon this prepared surface to define a strip which is reinforced by vertical reinforcing beams on centers both ways or in crossed relation thereby greatly adding to the strength of the slab so formed.

Various types of machines may be used to support the roller, such as is shown in Figure 1, or that as shown in Figure 2, and any suitable controls may be provided to regulate the flow of asphalt emulsion to the shaper roller. The roller 11^a shown in Figure 2 is used in a manner similar to that as described above, and the spray pipe 25 is adapted to spray emulsion upon the face of the roller 11^a where this emulsion is then pressed into the surface of the earth to form an impregnated protective coating 44 and thereby hold the surface of the earth in a securely formed and stabilized pattern.

In Figures 5 and 6 there is shown a modified form of the invention wherein a frame 45 carries a shaper roller 46 of the same general hollow type having similar ribs formed upon the surface thereof as that previously described with respect to the roller 11^a. In this form, however, the hollow axle 47 is fixed to the frame 45 and supports a burner 48. A supply pipe 49 is connected to the hollow axle 47 for supplying gas such as butane gas to the burner through the axle from a suitable supply tank 50. The roller 46 in this instance is open at each end, as at 51, and any desired number of burners may be supported in an upright position within the roller for heating the same when used with heavy asphalt. A suitable spray pipe 52 preferably is suspended in front of the roller 46 in this form and is supplied from the storage tank 54. The asphalt in this form is sprayed directly upon the surface of the earth or soil in front of the roller and prior to the formation of a pattern.

In Figure 7 there is shown a simple embodiment of the type of roller 55 which may be attached to a draft means by means of the frame 56. In this view the general arrangement of the ribs 57 is illustrated which is common to all types of shaper rollers referred to in the various modified forms.

In the type of machine shown in Figure 1, the frame thereof is supported by rubber tired wheels which may support the foundation shaper roller 11 above the ground or earth which is to be treated and shaped. The roller 11 may therefore be moved to a selected position and by retracting the wheels 12 and 12^a the foundation shaper roller 11 as well as the sheep foot traction roller 21, will be brought into contact with the surface of the ground or earth, and will bear the entire weight of the machine. The roller 21 will prepare the surface in advance of the roller and the emulsion will be spread upon the surface of the ground or earth and pressed into the same by the

roller 11, thereby stabilizing and shaping the ground or earth surface preparatory to receiving the concrete or other road forming material which is spread thereover. The ribs of the roller 11 will provide recesses in the earth or ground surface which is impregnated with the emulsion into which the road forming material will be molded to provide reinforcing beams to strengthen the road surface and to firmly anchor and stabilize the road surface or panel in position.

Therefore an important method is followed in laying the road surface strip or panel which includes the following steps:

1. The machine is moved to a selected position.
2. The surface of the ground or earth is treated or impregnated with an asphalt emulsion or other suitable material.
3. The shaper roller is brought into contact with the impregnated surface of the ground or earth.
4. The shaper roller is then rolled or propelled over the surface so treated to impress a pattern, preferably a waffle-like pattern, thereon, defining a plurality of depressed recesses extending at right-angles to each other in crossed relation.
5. A suitable road forming and shape conforming material such as concrete is spread upon the surface in which a pattern is impressed to conform upon its underside to said pattern.

As a further step in the method, it is preferable to prepare the ground or earth surface in advance of the shaper roller by means of a sheep foot traction roller to facilitate propulsion as well as to prepare, condition, or pulverize the surface or soil to receive the emulsion and the impression from the shaper roller.

It should be noted that various machines may be used including means for moving the shaper roller itself into direct contact with the ground or earth and retracting the roller, without departing from the spirit of the invention. Furthermore, the emulsion may be sprayed upon the ground or earth surface in advance of the shaper roller, or sprayed directly upon the shaper roller. The sheep foot roller may or may not be used as occasion may arise, but this sheep foot roller has been found to provide an efficient traction means as well as an efficient surface preparing means prior to the application of the emulsion.

Having described the invention, what is claimed as new is:

1. A machine for preparing earth surfaces upon which surfacing material is to be laid

comprising a frame, a roller carried by said frame, said roller comprising a drum-like body having a plurality of outwardly pressed longitudinal and a plurality of outwardly pressed circumferential spaced ribs formed therein, said ribs being hollow, an axle for said drum-like body, a plurality of spaced wheels carried by said axle within said body and having projecting portions fitting in said outwardly pressed circumferential spaced ribs to brace said circumferential spaced ribs, said wheels also having portions fitting in said longitudinal spaced ribs bracing the longitudinal spaced ribs, and longitudinal bracing members secured to the inner face of said drum-like body and inwardly of the longitudinal ribs bracing the body throughout its length and intermediate said spaced wheels.

2. A machine as defined in claim 1, wherein the wheels are provided with spokes, and the projecting portions comprise the ends of the spokes fitting in the outwardly pressed circumferential spaced ribs, and wherein the circumferential ribs taper outwardly, and the longitudinal ribs are provided with inwardly converging side walls thereby defining longitudinal ribs wide at their outer ends and receding toward said body to facilitate the rolling of a clean-cut pattern upon an earth surface area having clearly defined impressed channels in a waffle-like pattern to reinforce and anchor road surface material in place upon an earth surface area.
